UNITED STATES PATENT OFFICE.

FREDERICK P. WOOD, OF OAK PARK, ILLINOIS, ASSIGNOR TO AMERICAN CAN COMPANY, OF NEW YORK, N. Y., A CORPORATION OF NEW JERSEY.

BOX.

Application filed January 5, 1920. Serial No. 349,482.

To all whom it may concern:

Be it known that I, FREDERICK P. Wood, 434 South Grove Avenue, Oak Park, Illinois, a citizen of the United States, residing in 5 Oak Park, in the county of Cook and State of Illinois, have invented a new and useful Improvement in Boxes, of which the following is a specification.

This invention relates in general to fibre 10 boxes and more particularly to boxes adapted to the packaging of crackers and the like, although it will be manifest that it has other valuable uses.

A principal object of my invention is the 15 provision of a fibre cracker can or the like of strong and sturdy construction and without appreciable waste in the manufacture.

Another important object of my invention is the improvement in construction of containers of this character.

On the drawing,

Figure 1 is a partial perspective view of a box embodying my invention;

Fig. 2 is a plan view of the body blank;

Fig. 3 is a similar view of the cover blank;

Fig. 4 is a front to back section through the box;

Fig. 5 is a transverse vertical section; and 30 Fig. 6 is an enlarged detail section through a flap fastener at the top of the body.

The box shown on the drawing for the purpose of illustrating my present invention comprises a body 11 and a cover 12. The blank from which the body is made is shown in Fig. 2. This blank consists of a sheet scored on lines of fold 13 to set off four walls 14, all of the same dimension, and an edge flap 15. A top line of fold 16 and a bottom line of fold 17 are also provided and the lines of fold 13 are cut from the edges of the box to the lines of fold 16 and 17. The material above the line of fold 16 is narrow and the folding and cutting forms narrow flaps 18. Wider flaps 19 are provided at the bottom and these flaps are preferably of a width one-half that of the box.

The body is constructed by bending on the 50 lines of fold 13, securing the flap 15 to the opposite edge of the blank then bending up the flap 19 to close the bottom and gluing or otherwise securing these flaps together. The overlapping ends of the flaps 18 may be 55 and preferably are stapled together by front

and rear staples 21 and 27. It will be readily manifest that the bottom of the box is of double thickness by reason of the four flaps 19 each half the sectional area of the box.

The cover 12 is or may be made from the blank shown in Fig. 3. This consists of a sheet provided with a central body part 22 set off by side lines of fold 23 and end or front and back lines 24. Beyond the lines 23 are provided side flaps 25 and a front flap 26 and a back or end flap 27 are provided beyond the lines 24. Slots 28 separate the ends of the flaps 25 from the flaps 26 and 27, these ends extending out to the edges 70 of the blanks. The front flap 26 is substantially twice as wide as the side flaps 25 and is provided with a central line of fold 29. The rear flap 27 is similarly constructed having a central line of fold 31. In constructing the cover the side flaps 25 are bent up on the lines of fold 23 and the protruding ends are bent in towards the body 22. Front flap 26 is then bent up and folded back upon itself on the line 29 to enclose and 80 embrace the forward ends of the flap 25. If desired a lip 32 may be provided on the flap edge and a slit 33 made to receive this lip when the parts are folded. The flap 27 is also bent up and against the rear ends of 85 the flaps 25. The rear ends of the flaps 25 are glued or otherwise secured to this flap 27.

Part 34 located beyond the line of fold or hinge 31 extends up and this part is laid 90 along the rear outer face of the body and flush with its upper edge and is glued or otherwise secured in position. This arrangement is illustrated in Fig. 1. The cover may be closed by merely moving it about its 95 hinged connection on the line 31 as will be readily apparent.

It will be manifest that there is little or no waste in forming the blanks and the construction of the complete package is simple, 100 economical and the resulting box strong and durable.

It is thought that the invention and many of its attendant advantages will be understood from the foregoing description, and it 105 will be apparent that various changes may be made in the form, construction and arrangement of the parts without departing from the spirit and scope of the invention or sacrificing all of its material advantages, the 110

form hereinbefore described being merely a preferred embodiment thereof.

I claim:

1. A fibre box for crackers and the like, comprising a body made of a sheet folded on lines defining the vertical edges of the box and having flaps forming a bottom of double thickness and top flaps overlying and fastened together at adjacent ends and forming a continuous tying connection all around the box arranged inwardly of the body, and a cover arranged to fit down around and over said overlying top flaps.
2. A fibre box for crackers and the like, comprising a body and a cover therefor, said cover being formed of a sheet cut and folded on horizontal lines of fold to provide front back and side flaps, the ends of said flaps at the hinge side of the cover extending in and being secured to the inner side of the back flap, the back flap extending beyond the bent in ends of the side flap and provided therebeyond with a hinge line of fold, the part of said flap beyond said hinge line being secured to the back of the box.
3. A fibre box for crackers and the like,

comprising a body and a cover therefor, said cover being formed of a sheet cut and folded on side lines of fold to provide side flaps, all four of the ends of said flaps extending in and being secured to the inner sides of the bent up front and back flaps, the back flap extending beyond the bent in ends of the side flap and provided therebeyond with a hinge line of fold, the part of said flap beyond said hinge line extending up alongside and being secured to the back of the box.

4. A fibre box for crackers and the like comprising a bottom, front back and side vertical integral walls folded on vertical corner lines, and a cover, each of said walls having a top flap folded inwardly, the ends of said flaps being secured together to form a continuous connection entirely around the box which ties the front and back walls together and the side walls together, and a cover enclosing the top portions of said walls and resting on said continuous connection.

FREDERICK P. WOOD.
